UNITED STATES PATENT OFFICE

2,633,358

DEVICE FOR EXERCISING HAND AND
FINGER MUSCLES

William Tom Wright, Norwalk, Ohio

Application November 10, 1950, Serial No. 195,058

1 Claim. (Cl. 272—68)

1

This invention relates to a device for developing the muscles of the hands and fingers, and more particularly to a physiotherapeutic device for exercising the muscles of paralyzed hands and fingers.

An object of this invention is to provide a physiotherapeutic device for use by paralyzed individuals in exercising affected muscles of the hand, to thereby regain normal use of the affected limbs.

Another object of the invention is to provide a physiotherapeutic device for exercising paralyzed hands and fingers to help strengthen the grip of the hand and to aid in relaxing abnormal muscular conditions.

Another object of this invention is to provide a physiotherapeutic device for increasing digital strength of the hand, to thereby particularly adapt the device for use in cases of partial paralysis.

Another object of this invention is to provide a physiotherapeutic device for exercising the muscles of paralyzed hands and fingers which is relatively simple in structure and cheap to manufacture.

The above and still further objects and advantages of the present invention will become apparent upon consideration of the following detailed description of the invention, when taken in conjunction with the accompanying drawings, wherein:

Figure 1 is a side elevational view of the physiotherapeutic device of the present invention, shown engaged by the hand to be exercised; and

Figure 2 is a side elevational view of the hand-exercising physiotherapeutic device shown in Figure 1, with parts broken away and shown in section.

Referring now more particularly to the drawings, wherein like reference numerals have been used throughout the several views to designate like parts, there is shown the physiotherapeutic device of the present invention, generally designated by the reference numeral 10 and engaged by the hand 11, the hand including the fingers 12 and thumb 13.

The hand-exercising therapeutic device 10 includes an elongated length of flexible wire, preferably fabricated of spring steel and generally designated by the reference numeral 15. The length of wire 15 includes a substantially straight portion 16 which extends inwardly from one end thereof and terminates at a point adjacent to and spaced from said one end. The straight portion 16 is circular in cross-section and has its free end threaded, as designated by the reference nu-

2

meral 17. Circumposed about the end-adjacent portion 16 is a grip 18 which is preferably fabricated of a rubber-containing material and is supported on the straight portion 16. The grip 18 is maintained against displacement from its supported position on the elongated length of wire 15 by means of the abutment element 19 which bears against the end of the grip 18 adjacent thereto and is supported in threaded engagement on the threaded end 17 of the straight portion 16.

The other end-adjacent portion 20 of the wire 15 is bent into spaced relation with respect to the grip 18 and is bent back and secured upon itself to form a closed loop 21 adapted to receive the thumb 13 of the hand 11 to be exercised. As clearly shown in Figure 2, the free end 23 of the end-adjacent portion 20 is bent into a position wherein it abuts against the adjacent section of wire 15, the free end 23 being held in its loop-forming position by means of the sleeve 24 which is circumposed about and secured to the wire 15 contiguous to the end-adjacent portion 20, the sleeve embracingly receiving the free end 23 of the end-adjacent portion 20.

25 The portion of the shank intermediate the grip 18 and the thumb-engaging loop 21 is square in cross-section and is arcuately bent, as indicated by the reference numeral 25, to position the thumb-engaging loop 21 in spaced relation with respect to the portions of the hand grip 18 contiguous to the inner end of the straight portion 16, that is, that end of the portion 16 that merges into the shank portion 25.

Although only one embodiment of the hand-exercising therapeutic device of the present invention has been described, it is readily apparent that numerous modifications can be made without departing from the spirit of the invention as set forth in the appended claim.

40 What I claim is:

In a hand-exercising therapeutic device, an elongated wire fabricated of spring steel including a substantially straight portion extending inwardly from one end thereof and having its inner terminus at a point adjacent to and spaced from said one end, a grip adapted to be engaged by the fingers of a hand to be exercised circumposed about said straight portion and secured thereto, a straight shank arranged normally to said straight portion and disposed a substantial distance beyond said point in a direction away from said one end, a spring integral at opposite ends with and connecting said straight portion and shank for flexing of the shank against the force of the spring in the direction of the straight portion, an

end portion integral at one end with the other end of the shank and extended angularly thereto in a direction away from said straight portion, and a thumb-receiving loop integral with the other end of the end portion, said loop being positioned by said spring, shank, and end portion in laterally spaced relation to the portion of the hand grip contiguous to said inner terminus of the straight portion.
